UNITED STATES PATENT OFFICE

147,125

DESIGN FOR A CREVICE TOOL FOR
VACUUM CLEANERS

Richard E. Harvuot, Inglewood, Calif., assignor
to Interstate Aircraft and Engineering Corp.,
El Segundo, Calif., a corporation of California

Application August 26, 1946, Serial No. 132,853

Term of patent 14 years

(Cl. D9—2)

To all whom it may concern:

Be it known that I, Richard E. Harvuot, a citizen of the United States and resident of the city of Inglewood, county of Los Angeles, State of California, have invented a new, original, and ornamental Design for Crevice Tool for Vacuum Cleaners, of which the following is a specification, reference being had to the accompanying drawings, forming a part thereof, in which

Fig. 1 is a perspective view of the crevice tool for vacuum cleaners, showing my new design;

Fig. 2 is a top plan view;

Fig. 3 is a bottom plan view;

Fig. 4 is a side elevation;

Fig. 5 is a rear end elevation; and

Fig. 6 is a front end elevation thereof.

I claim:

The ornamental design for a crevice tool for vacuum cleaners, substantially as shown.

RICHARD E. HARVUOT.
